UNITED STATES PATENT OFFICE

KURT LANDSMANN, OF MANNHEIM, GERMANY, ASSIGNOR TO AKTIENGESELLSCHAFT BROWN BOVERI & CIE., OF BADEN, SWITZERLAND, A JOINT-STOCK COMPANY OF SWITZERLAND

ELECTRIC RELAY APPARATUS

Application filed August 18, 1926, Serial No. 129,975, and in Germany September 3, 1925.

This invention relates generally to relay apparatus, and particularly to apparatus designed for protection of networks or portions thereof or connected installations, against abnormal voltage or current conditions.

One general object of the invention is the provision of an arrangement whereby the relay apparatus is itself safeguarded against destruction or disablement from excessive 10 current or voltage effects.

Another object is the provision of an arrangement whereby relay apparatus designed for carrying relatively low current quantities may be installed in systems normally carrying 15 or subject to much higher current conditions.

A particular object of the invention is the provision of a construction wherein either or both of the advantages indicated above may 20 be attained by comparatively simple and completely reliable means.

Other and further objects will be pointed out or indicated hereinafter, or apparent to one skilled in the art upon an understanding 25 of the invention.

In the drawing forming a part of this specification I illustrate in diagrammatic fashion certain arrangements of apparatus in which the invention may be embodied, but 30 these are presented for purpose of illustration only and are not to be construed as imposing on the claims any limitations not necessitated by the prior art.

In the drawing,
35 Fig. 1 is a diagram illustrating a relay connection for the operation of a tripping device intended to be brought into operation upon the current in the supply lines or network reaching a predetermined quantity;

40 Fig. 2 is a diagrammatic illustration of an arrangement wherein the tripping relay is of the no-volt type; and

45 Fig. 3 is a diagrammatic illustration of an arrangement of a type wherein the winding of the tripping magnet is of the auto-transformer type.

In types of protective apparatus quite generally employed, an electro-magnet is employed for operation of a switch which will 50 isolate the apparatus to be protected, such

electro-magnet sometimes being called the tripping magnet or tripping relay. In conjunction with it is utilized a detecting relay or contactor, which is responsive to the condition in the system against which it is intended to safeguard the apparatus, such detecting relay operating, upon the occurrence of that condition, to bring the tripping relay into operation. It is a matter of convenience and economy to operate both the 55 tripping and detecting relays from the same supply source. Both, however, must have certain limitations as to the current and voltage values which they can handle without damage or without deterioration of contacts, 60 and with which they can operate with certainty and reliability. Upon the occurrence of various disturbances such as short-circuits, however, the current may rise to many times the value for which the relays are designed, 65 and the provision of suitable contacts for handling such high currents in the apparatus, or the provision of transformers for reducing the current effects, present various difficulties and involve undesirable complications and increased cost. By virtue of the 70 present invention I am enabled to energize the relays from the system in which the effects occur without subjecting them to injurious current or voltage influences and so without involving complications.

In the arrangement illustrated in Fig. 1 the reference numeral 10 designates the lines of the system, in this instance an alternating current system, and 11 designates the 75 transformer for the protective apparatus. The tripping coil is designated 12, and when energized to a predetermined degree is intended to operate or initiate operation of the switch opening device. The tripping coil is 80 included in the secondary circuit of the transformer 11, in which is also connected the coil 14 of the contactor or detecting relay, having a movable contact member 14^a. The tripping magnet has wound on the same core 85 with the coil 12, a secondary winding 15 which forms part of a secondary circuit normally closed by the contact member 14^a. Under normal line conditions, the reduced current from the secondary of the transformer 90

11 flows through the coil 12 of the tripping magnet, but its magnetizing effect is counteracted by the short-circuited compensating secondary winding 15. Thus the current 5 passing through the contacts of the detecting or overload relay is not the same as that passing through the coils 12 and 14, and through the arrangement of the coils 12 and 15 may be held at such a low value as to 10 preclude injurious effects on the contacts. The control spring 14^b of the overload relay is set, of course, to hold the secondary circuit closed until the power of the relay magnet reaches a predetermined value. When 15 this value is exceeded, however, as occurs upon an overload on the lines 10, the relay contacts will be opened, and the neutralizing effect of the secondary coil 15 on the tripping magnet will be eliminated, whereupon the 20 tripping magnet will be energized and operate the tripping mechanism.

Wherever overload relays are employed they are nearly always of the time-limit type, but are nevertheless frequently designed to 25 trip instantaneously in the event of a heavy overload. With the present type of apparatus, this condition may be fulfilled in a very simple manner by suitably designing the windings or circuits of the tripping magnet. 30 The current induced in the secondary winding 15 cannot completely neutralize the magnetizing effect of the primary current in coil 12, but reduces it to a fraction of its value. If the primary current in coil 12 is increased, 35 this excess or unneutralized magnetization also increases until, at a certain value of the primary current, it is sufficient to operate the tripping mechanism. By suitably choosing the number of turns on the two windings, and 40 by the insertion of resistances, choke coils, or similar simple devices, it is possible to set the current value, above which the tripping mechanism operates instantaneously without preliminary opening of the contact 14^a, at 45 any desired quantity to meet the conditions in hand.

In the arrangement illustrated in Fig. 2, the tripping magnet is a no-volt magnet having the primary winding 16 and the secondary winding 17, the former being connected across the lines 10 and the latter being included in a circuit which may be closed by the movable contactor 18^a of the detecting or overload relay 18, the coil of the latter being energized from the line through the transformer 19. The contactor 18^a is normally held open by its spring. As the current taken by the no-volt magnet is very small when the secondary circuit is open, and increases greatly when the secondary is closed, it follows that the magnetization of the iron core will vary to a much less extent than is the case with the arrangement shown in Fig. 1. Under some circumstances the 60 closing of the secondary circuit might cause 65

such a rise of current that the winding would be overloaded. Accordingly, it is advisable to insert an ohmic or inductive resistance 20 in series with the primary winding 16, so that the variation of the primary current on opening and closing of the secondary circuit is kept within desirably narrow limits. An appropriate type of resistance for this purpose is one having a high temperature coefficient which varies in resistance in accordance with the current in such a way that the latter remains practically constant within certain limits. In this arrangement the occurrence of an overload on the line causes the overload relay 18 to be energized to a degree overcoming the contactor spring and closing the contacts of the secondary circuit. Upon this occurrence the current in the primary 16 will increase to the point at which the tripping mechanism is operated. This 70 operation and the subsequent opening of the contactor 18^a is accomplished without subjecting the contacts to heavy current. 75

In the arrangement illustrated in Fig. 3 the winding 21 of the tripping magnet is arranged as an auto-transformer, one pole of the secondary of the transformer 22 being connected at the neutral point of the winding and the opposite ends of the latter normally being connected to the other pole of the transformer secondary. The connection of the lower end of winding 21 is by way of the movable contactor 24^a of the overload relay 24 so that, so long as the current in the winding of the overload relay is below the critical point, the halves of the auto-transformer winding 21 neutralize each other. Upon the appearance of an overload, however, the neutralizing lower half of the auto-transformer winding is cut out by the opening of contactor 24^a, rendering the still active portion of the winding 21 effective to induce the necessary magnetization of the tripping magnet and operate the tripping mechanism. 80 85

What I claim is:

1. In electric relay apparatus, tripping and overload relays each having an operating winding, said overload relay including a switch and spring means normally holding the same in closed position, a transformer having a secondary winding, said relay-operating and secondary windings being connected in series with respect to each other to constitute a closed circuit, and a winding associated with the operating winding of said tripping relay and connected across said switch to constitute a second closed circuit. 100

2. In a protective relay system, a switch arranged in a circuit to be protected, a tripping relay having an operating winding, said relay being operable to trip said switch, a detecting relay having an operating winding energized only upon overload in the circuit to be protected, a transformer connected into the circuit to be protected, said transformer 105 110 115 120 125 130

having a secondary winding connected in series with the operating winding of said relays, and a compensating winding arranged in inductive relation with the operating winding of said tripping relay, the current flow in said compensating winding being controlled by operation of said detecting relay.

3. In a protecting relay system, a switch arranged in a circuit to be protected, a tripping relay having an operating winding, said relay being operable to trip said switch, a detecting relay having an operating winding operable only upon overload in the circuit to be protected, a switch controlled by operation of said detecting relay, a transformer connected into the circuit to be protected, said transformer having a secondary winding connected in series with the operating windings of said relays, and a compensating winding arranged in inductive relation with the operating winding of said tripping relay, said compensating winding and said switch connected therewith forming a closed circuit.

In testimony whereof I have hereunto subscribed my name this 24th day of July, A. D. 1926, at Stuttgart, Germany.

KURT LANDSMANN.
